UNITED STATES PATENT OFFICE

CHARLES FRANCIS JENKINS, OF WASHINGTON, DISTRICT OF COLUMBIA, ASSIGNOR TO JENKINS LABORATORIES, OF WASHINGTON, DISTRICT OF COLUMBIA, A CORPORATION OF THE DISTRICT OF COLUMBIA

DUPLEX SCANNING DISK

Application filed September 6, 1928. Serial No. 304,353.

This invention relates to radiovision and television transmitting apparatus, and has for its main object means for greatly increasing the efficiency of the apparatus.

5 The method of scanning the object to be transmitted by a point source of light was disclosed in French Patent No. 390,435, 1908. In this method the light-cell is necessarily illuminated only by the reflected light from 10 the scanned subject.

To increase this efficiency a lens-disk may be employed to project the illuminating spot on the light cell, but it is difficult to keep the moving spot centered on the light cell.

15 To overcome this difficulty it has been found desirable to pass both the incident and the reflected light through the same scanning disk.

With this and other objects in view, the 20 invention consists of the novel combination of parts herein disclosed, and particularly pointed out in the claims.

In the schematic drawings Figure 1 is an 25 elevation of the light-source side of the disk; Figure 2 an elevation from the light-cell side; Figure 3 a large-aperture scanning disk with lenses over each aperture; and Figure 4 a scanning disk having elementary area apertures therein.

30 In the figures, A is a source of light; B a mirror for turning the direction of the light beam through the lenses of scanning disk C; D a large lens located in alignment with the light coming through the scanning disk; E an object to be scanned; F a second scanning disk having elementary apertures therein; G a lens lying between this apertured-disk and the light cell H. The lenses on disk C might, if desired, be arranged in a full or partial 35 additional spiral turn.

Assuming the disks to be put into rotation, a spot of light from the source A is swept 40 across subject E transversely and from top to bottom; and its reflection received on cell H after passing through a lens on disk C at diametrically opposite the moving lens which produces the scanning.

This comes about in spite of the fact that 45 one radius of the disk is going down and the opposite radius is going up, because the equiv-

alent focus of lens D and lenses on disk cause a reversal of light movement beyond the point K.

Absolutely perfect synchronism is attained, however, because the light projected 55 through a lens of one edge of disk C is reflected to the cell through a lens on exactly the opposite edge of the disk.

The location of the disk F between the lens disk and the cell limits the light to an 60 elementary area no matter how large the illumination spot on figure E may be.

The location of a suitable size of lens at 65 G concentrates all the reflected light, passing the disk F, onto the stationary cell H in spite of the movement of the disk.

It has been found that (1) the use of a single scanning disk; (2) a reversing lens at D; and (3) a concentrating lens at G has greatly increased the efficiency of this method 70 of subject scanning.

What I claim, is:—

1. In spot scanning of electrically transmitted subjects, the combination of a rotatable scanning disk common to both spot illumination and spot cell-pickup; a source of light from which light is passed through said scanning disk; a disk having apertures in alignment with the scanning elements of said scanning disk and a light-sensitive cell upon which light from the source falls after passing through the said scanning disks. 75

2. In spot scanning of electrically transmitted subjects, the combination of a rotatable scanning member common to both spot illumination and spot cell-pickup; a source of light from which light is passed through said scanning member; a light-sensitive cell upon which light from the source falls after 80 passing through the same scanning member, and a second scanning member lying between the lens and the light cell, and having apertures therein of elementary area. 85

3. In spot scanning of electrically transmitted subjects, the combination of a rotatable scanning member; a source of light located to pass light therethrough; and a lens in alignment with said light source and said scanning member, and of a diameter approxi- 95 100

mately greater than the space between scanning apertures.

4. In spot scanning of electrically transmitted subjects, the combination of a rotatable scanning member; a light-sensitive cell located to receive light passing through said scanning member; and a lens approximately greater than the space between said scanning member and the cell, lying between and in alignment with the cell and scanning member working apertures.

5. The method of scanning which comprises rotating an analyzing device between a light source and an object to expose the said object to a moving spot of light, positioning a light sensitive device in the path of the reflected rays, said reflected rays also passing through said analyzing device and limiting the area of the reflected beam reaching said light sensitive device through said member, by passing the reflected beam through an apertured mask between the analyzing device and the light sensitive device.

6. The method of scanning which comprises projecting a light beam through a large apertured scanning device on to an object to be scanned, said scanning device being positioned to permit the rays reflected from said object to pass through a large aperture therein different from the aperture through which the projected rays are passed, and rotating a shutter between said scanning device and a light sensitive device to restrict the area of the reflected beam passing through the large apertures of the scanning device.

7. In a scanning system comprising a source of light, a large apertured scanning member between said source and an object to be scanned and a small apertured scanning member between said first scanning member and the light sensitive device.

8. A scanning system comprising a rotating scanning device having large aperture therein, means for projecting a scanning beam through one aperture of said device onto an object to be scanned, the light reflected from said object passing through another aperture on said disk on the opposite edge thereof and means for projecting the rays passing through said other aperture onto a light sensitive device.

9. A scanning system according to claim 8 in which the large apertures are provided with lenses.

10. A scanning system according to claim 8 in which a small apertured scanning member is rotated between the large apertured scanning member and the light sensitive device.

11. A scanning system comprising a light sensitive device, an object whose image is to be transmitted, a first large apertured scanning member, a second small apertured scanning member, both members being positioned

between the object and the light sensitive device, a source of scanning light, and means for projecting light from said source through one edge of the large apertured member onto the object and reflecting light from said object through an aperture on the opposite edge of said member.

In testimony whereof I have affixed my signature.

CHARLES FRANCIS JENKINS.

DISCLAIMER

1,785,262.—*Charles Francis Jenkins*, Washington, D. C. DUPLEX SCANNING DISK.
Patent dated December 16, 1930. Disclaimer filed August 16, 1934, by the
assignee, *Radio Corporation of America*.

Hereby enters this disclaimer to that part of the claim in said specification which
is in the following words, to wit:

“8. A scanning system comprising a rotating scanning device having large aper-
ture therein, means for projecting a scanning beam through one aperture of said device
onto an object to be scanned, the light reflected from said object passing through
another aperture on said disk on the opposite edge thereof and means for projecting
the rays passing through said other aperture onto a light sensitive device.”
